UNITED STATES PATENT OFFICE

148,914

DESIGN FOR A CONTROL UNIT

Charles J. Daubenberger, Pacific Palisades, Calif.,
assignor to Dauby Equipment Company, Santa
Monica, Calif., a corporation of California

Application October 18, 1946, Serial No. 134,063

Term of patent 7 years

(Cl. D26—5)

To all whom it may concern:

Be it known that I, Charles J. Daubenberger, a citizen of the United States, residing at Pacific Palisades, in the county of Los Angeles, State of California, have invented a new, original, and ornamental Design for a Control Unit, of which the following is a specification, reference being had to the accompanying drawings, in which:

Fig. 1 is a perspective view of a control unit, showing my new design;

Fig. 2 is a side view showing one side;

Fig. 3 is a side view showing the opposite side;

Fig. 4 is a top view; and

Fig. 5 is an end view thereof, taken from the left-hand end of Fig. 2.

I claim:

The ornamental design for a control unit, substantially as shown.

CHARLES J. DAUBENBERGER.
